INVENTOR.

UNITED STATES PATENT OFFICE.

ROSE ZREBIEC, OF WOODLAWN, PENNSYLVANIA.

WINDOW-SCREEN FRAME.

1,324,950.

Specification of Letters Patent. Patented Dec. 16, 1919.

Application filed October 2, 1919. Serial No. 327,979.

To all whom it may concern:

Be it known that I, Rose ZREBIEC, a citizen of the United States, residing at Woodlawn, in the county of Beaver and State 5 of Pennsylvania, have invented certain new and useful Improvements in Window-Screen Frames, of which the following is a specification.

This invention relates to new and useful 10 improvements in frames for window screens and the primary object thereof is to provide a device of the character described and in a manner as hereinafter set forth which may be readily and conveniently attached 15 to ordinary window fly screening and form a very substantial structure.

Further objects of this invention are to provide a frame for window screens which is simple in its construction and arrangement, 20 strong, durable and efficient in its use and comparatively inexpensive to manufacture.

To the accomplishment of these and such other objects as may hereinafter appear the 25 invention consists of the novel construction, combination and arrangement of parts herein specifically described and illustrated in the accompanying drawing, wherein is shown an embodiment of the invention, but it is to be understood that the device shown is merely 30 illustrative and that various changes in the form, proportion and minor details of construction may be resorted to without departing from the principle or sacrificing any 35 of the advantages of the invention, which come within the scope of the claims hereunto appended.

In the drawing forming a portion of this specification and wherein like numerals of 40 reference designate corresponding parts throughout the several views:

Figure 1 is an elevational view of a window screen, including a frame constructed in accordance with this invention.

Fig. 2 is a fragmentary enlarged view of one of the corners.

Fig. 3 is a sectional view on line III—III, Fig. 2.

Fig. 4 is a sectional view on line IV—IV,

Fig. 2.

Fig. 5 is an inner view of one of the frame members partially clamped together.

Fig. 6 is a sectional view on line VI—VI, Fig. 5.

Fig. 7 illustrates the end of the frame 55 member in the expanded position.

Fig. 8 is a sectional view on line VIII—VIII, Fig. 2.

Fig. 9 is a fragmentary view showing the 60 method of securing the corners of the frame together.

Referring more in detail to the drawing there is shown in Fig. 1 a window fly screen in accordance with this invention and comprising the foraminous body or screening 65 1, the frame end members 2 and 3, and the frame side members 4 and 5.

The construction of the frame end members 2 and 3 and the frame side members 4 and 5 is identical, and the former may 70 vary in length with respect to the latter to conform, when all of the members are assembled to the contour of the opening in which the screen is adapted to be used.

Each of the frame members is constructed 75 from a strip of sheet metal adapted to be folded together centrally and longitudinally thereof, as shown in Figs. 5 and 6 of the drawing, to form the inner and outer walls 6 and 7, respectively.

The edges 8 and 9, of respective walls 6 and 7 of the frame members, with the exception of respective end portions 10 and 11, thereof, are turned inwardly upon the inner face of the walls 6 and 7, and are provided for the purpose of substantially reinforcing and stiffening the frame members. 80

The edge 8, of the wall 6, is formed with a plurality of teeth 12, the points 13 of which, when engaging the screening 1 as 90 shown in Figs. 3 and 4, stand slightly away from the inner face of the wall 6, and when not used to secure the screening 1, lie flatly against the inner face of the wall 6.

The edge 9, of the wall 7, is likewise 95 formed with a plurality of teeth 14, the points 15 of which either lie flatly against the inner face of the wall 7 or stand slightly away therefrom, depending on whether or not said teeth 14 are utilized for securing 100 the screening 1 therein.

For the purpose of securely clamping the walls 6 and 7, forming the frame member, together after the screening 1 has been

engaged by either the teeth 12 or 14, certain of the teeth 12 and 14 are adapted to be bent at right angles with respect to their respective walls and register with and extend 5 through slots 16 or 17, respectively formed in the walls 6 and 7, after which said teeth are clenched to clamp said walls securely together.

Teeth are provided on the inner face of 10 both of the walls 6 and 7, so that after many of the teeth on one wall have been broken or become unfit for use, due to changing the screening therein, the teeth of the other wall may be used, thereby doubling the life and utility of the frame members.

Each end of the frame members is formed with the elongated end portion 10 and a short end portion 11. A slot is formed in 20 intermediate of the end portions 10 and 11 and is of a length commensurate to the width of the frame member when folded together longitudinally as herein before described.

25 For securely connecting the frame members together the elongated end portion 10 of the side frame member passes through the slot 18 in the end frame member, while the elongated end portion 10 of the end 30 frame member passes through the slot 18 in the side frame member, after which each of the elongated end portions is bent over

to overlap its short end portion, as shown in Figs. 8 and 9 of the drawing.

It will here be noted that a screen frame constructed in accordance with this invention may be readily and conveniently assembled, and broken screening easily replaced therein, and may be attached to the window framing, if desired, in any suitable manner.

What I claim is:—

1. A screen frame comprising a plurality of frame members, each of which consists of a strip of bendable metallic material bent at its longitudinal center upon itself and further having each longitudinal marginal portion thereof bent inwardly and provided with fastening barbs, said strip at each side of its longitudinal center provided with a plurality of openings.

2. A screen frame comprising a plurality of frame members, each of which consists of a strip of bendable metallic material bent at its longitudinal center upon itself and further having each longitudinal marginal portion thereof bent inwardly and provided with fastening barbs, said strip at each side of its longitudinal center provided with a plurality of openings and at each end slitted to form a pair of bendable end portions one of greater length than the other.

In testimony whereof I affix my signature.
ROSE ZREBIEC.
